UNITED STATES PATENT OFFICE.

RAFAEL FRÉYTEZ PINEDA, OF BARQUISIMETO, VENEZUELA.

HOLDER FOR CIGARS AND CIGARETTES.

1,372,544.

Specification of Letters Patent. Patented Mar. 22, 1921.

Application filed October 7, 1919. Serial No. 329,155.

To all whom it may concern:

Be it known that I, RAFAEL FRÉYTEZ PINEDA, a citizen of Venezuela, South America, and a resident of Barquisimeto, Estado Lara, 5 Venezuela, South America, have invented a new and Improved Holder for Cigars and Cigarettes, of which the following is a description.

My invention relates to a sanitary holder 10 for cigars and cigarettes, the general object of the invention being to avoid the bad effects of the nicotine on the smoker.

The stated object is attained by providing a holder in the form of a stem comprising 15 a mouthpiece and a front member adapted to receive the cigar or cigarette, together with means interposed between the front member and the mouthpiece and constituting a smoke washer through which the 20 smoke is caused to pass for eliminating the nicotine and incidentally cooling the smoke.

A further important object of the invention is to provide a smoke washer so mounted on the stem as to be disposed in a 25 perpendicular or approximately perpendicular position to the stem when the holder is to be used or swung upwardly to lie alongside of and approximately parallel with the stem, thereby giving the holder a compact 30 form to be conveniently carried in the pocket or in a small case made for the purpose.

More specifically, I have in view an embodiment of the invention reflecting important considerations with respect to simplicity 35 of construction and durability as well as the convenience of assembling the parts or disassembling the same for cleaning or repair.

Reference is to be had to the accompanying drawings forming a part of this specification, it being understood that the drawings are merely illustrative of one example 40 of the invention.

Figure 1 is a perspective view of a holder 45 for cigars or cigarettes embodying my invention;

Fig. 2 is an enlarged transverse vertical section on the line 2-2, Fig. 1;

Fig. 3 is a side elevation with parts in 50 section as indicated by the line 3-3, Fig. 1;

Fig. 4 is a fragmentary sectional plan view, the section being taken on the line 4-4, Fig. 3.

In carrying out my invention in accordance 55 with the illustrated example, a stem is provided including a front member 10 adapted to receive a cigar or cigarette and a

mouthpiece 11 having respectively smoke passages 12 and 13 out of direct communication with each other. On the front member or on the mouthpiece at the juncture of 60 these is a preferably enlarged member 14 extending laterally from which is an arm 15 round in cross section and preferably slightly tapering toward the outer end. In the member 14 and its arm 15 is a transverse 65 smoke passage 12^a communicating with the smoke passage 12 when the stem and front member are assembled and a smoke passage 13^a communicating with the smoke passage 13. Said smoke passages 12^a, 13^a terminate 70 in downwardly directed smoke passages 12^b, 13^b, extending through the periphery of the arm 15.

On the arm 15 is a hanger element 16 comprising a ring 16^a embracing and snugly fitting said arm and a depending nipple 16^b having thereon a smoke washer designated generally by the numeral 17 comprising a tubular neck 17^a engaged with the nipple 16^b and a preferably spherical water chamber 17^b formed upon or secured to the lower end of said neck. In the illustrated form the neck 17^a is detachably secured to nipple 16^b by a threaded connection as at 16^c and also, advantageously, chamber 17^b is formed with 85 a neck at the top detachably secured by a threaded connection as at 17^d with the neck 17^a. The nipple 16^b has a vertical passage 18 which in the pendent position of the nipple extends vertically, establishing communication between the smoke passage 12^b and the neck 17^a of the washer and a similar vertical passage 19 in said nipple leads from the neck 17^a to the smoke passage 13^b for conducting the smoke to the mouthpiece 11. 95 A tube 20 extends from the smoke passage 18 downwardly through the stem 17^a to near the bottom of the water chamber 17^b to be immersed at its lower end in the water indicated at A contained in said chamber. 100 Said tube 20 at its upper end extends into the nipple 16^b and is supported thereby.

With the described construction when the washer 17 is pendent on the stem the smoke passages, 18, 19 will register with the smoke passages 12^b, 13^b and when the device is in use smoke will be drawn through the passage 12 of the front member 10 and through the described passages in arm 15 and hanger 16 to and through the depending tube 20 and caused 105 to bubble through the water A to pass outwardly through passage 19 and the mouth-

piece 11, thereby eliminating the nicotin from the smoke and desirably cooling the latter. When the holder is not required for use, the washer 17 is raised to a position alongside the stem as indicated by dotted lines in Fig. 3, so that the holder is in compact form to be carried in a pocket or in a small case, the mounting of the hanger 16 on the arm 15 to turn on the latter, permitting the washer to be swung to either of the two positions. The tapering form of the arm 15 and ring 16^a insures a tight joint therebetween so that there is no leakage of water and in the raised position of the washer, it will be seen that the passages 18, 19 are out of communication with the passages 12^b, 13^b. The hanger 16 is detachably held on the arm 15 by suitable means, there being shown for the purpose a nut 21 on the threaded outer end of said arm.

In using my device different results are obtained, according to the character of the liquid placed therein, whereby to vary the taste of tobacco and the matter retained by the liquid. For example, if water is put in the chamber 17^b, since water does not dissolve out the nicotin the latter passes with part of the contained ammonium and pyridin to the mouthpiece and the taste of smoke is altered very little while at the same time the injurious qualities of the smoke are at least diminished. On the other hand, if tannin solutions of various degrees of strength are employed instead of water, quite different taste is obtained and also a grade of opiation varying according to the strength of the solution. This allows the smoker to gradually rid himself of the smoking habit until he does not feel a craving for smoking.

I would state in conclusion that while the illustrated example constitutes a practical embodiment of my invention, I do not limit myself strictly to the mechanical details herein illustrated, since manifestly the same can be considerably varied without departure from the spirit of the invention as defined in the appended claims.

Having thus described my invention, I claim:

1. A holder for cigars and cigarettes, including a stem presenting a front member adapted to receive a cigar or cigarette, and a mouthpiece, said front member and mouthpiece having smoke passages out of direct communication with each other and an intermediate washer establishing communication between said smoke passages and swingable from a depending position on the stem to a position adjacent to the stem. 50

2. A holder for cigars and cigarettes, including a stem presenting a front member adapted to receive a cigar or cigarette, and a mouthpiece, said front member and mouthpiece having smoke passages out of direct 55 communication with each other, a member presenting a lateral arm and having smoke passages communicating respectively with the first-mentioned smoke passages, and a smoke washing means suspended on said 60 arm at a side of the stem and having passages communicating respectively, through the passages in said member with the first-mentioned smoke passages to establish communication between the latter, said washing 65 means being turnable on said arm from a position pendent on the stem to a position approximately parallel with the stem. •

3. A holder for cigars and cigarettes, including a stem presenting a front member 80 adapted to receive a cigar or cigarette, and a mouthpiece, said front member and mouthpiece having smoke passages out of direct communication with each other, a member presenting a lateral arm and having smoke 85 passages communicating respectively with the first-mentioned smoke passages, a hanger on said arm at a side of the stem, said hanger presenting a ring fitting said arm and adapted to be turned thereon, and a 90 smoke washer carried by said hanger, the hanger having smoke passages adapted to be brought into or out of register with the smoke passages of the arm by the turning of the hanger on the arm.

RAFAEL FRÉYTEZ PINEDA.
